DESIGN FOR A COOKING UTENSIL
CLOSURE

James Harvey Chandler, Oak Park, and Myron J. Zimmer, Wooddale, Ill., assignors to The Edward Katzinger Company, Chicago, Ill., a corporation of Illinois

Original application April 5, 1944, Serial No. 113,146. Divided and this application June 7, 1944, Serial No. 113,893

Term of patent 14 years

(Cl. D44—8)

To all whom it may concern:

Be it known that we, James Harvey Chandler and Myron J. Zimmer, citizens of the United States, residing at Oak Park, in the county of Cook and State of Illinois, and Wooddale, in the county of Du Page and State of Illinois, respectively, have invented a new, original, and ornamental Design for a Cooking Utensil Closure, of which the following is a specification, reference being had to the accompanying drawing, forming part thereof.

This application is a division of our application Ser. No. D113,146, filed April 5, 1944.

Fig. 1 is a top plan view of a cooking utensil closure showing our new design.

Fig. 2 is a side elevational view of the same.

Fig. 3 is a side elevational view of the same when turned about its vertical axis through an angle of 90 degrees relative to its position as shown in Fig. 2.

We claim:

The ornamental design for a cooking utensil closure, as shown.
